UNITED STATES PATENT OFFICE.

EDGAR R. CREAMER, OF CONNERSVILLE, INDIANA, ASSIGNOR TO THE GEORGE R. CARTER COMPANY, OF CONNERSVILLE, INDIANA, A CORPORATION OF INDIANA.

WINDOW MOLDING FOR AUTOMOBILES.

Application filed March 24, 1927. Serial No. 177,874.

This invention relates to improvements in window moldings for automobile and similar uses.

One object of the invention is to construct a molding, which is capable of being bent into a variety of forms and shapes without buckling or wrinkling, and to have it sufficiently reinforced and stiffened to insure it lying properly after being placed in its final position, 10 such that there will be substantially no tendency for the fastening devices to draw it out of shape or change the form assumed by it. For this reason the improved molding is particularly adapted to closed cars using broad- 15 cloth, mohair, plush or velvets for interior trimming.

Other objects and advantages will be in part indicated in the following description and in part rendered apparent therefrom in 20 connection with the annexed drawings.

To enable others skilled in the art so fully to apprehend the underlying features hereof that they may embody the same in the various ways contemplated by this invention, 25 drawings depicting a preferred typical construction have been annexed as a part of this disclosure and, in such drawings, like characters of reference denote corresponding parts throughout all the views, of which:—

30 Figure 1 is an interior view of a closed car showing the rear and one side window. Fig. 2 is a detail view of the molding bent into one form and Fig. 3 is a detail of the molding bent into a different form.

35 It is apparent that a molding suitable for a rear window, such as illustrated, should be capable of being bent into the position shown without distortion and with the requisite amount of stiffness and with the least tend- 40

ency to resume its normal position, especially after the fastening devices are inserted. To accomplish these objects, there is shown a filler 1 preferably made from fifty pound crepe kraft paper having substantially two 45 hundred per cent stretch and this paper is coated with cement or some similar adhesive to cause the folds of paper to retain their folded shape. The covering 2 is preferably plush or body cloth and the two independent 50 steel wires are encased within the filler preferably at the time the filler is being formed. These wires may be of steel or brass in spring wire and preferably are No. 17 gauge or .051. The fastening devices are preferably finished

nails 4 because with such devices the cloth 55 will have a tendency to close over the head of the nails, thereby entirely concealing the fastening devices but the molding may be applied with ordinary screws or nails or any other desired form of fastening device. 60

In Fig. 3 there is shown the independent action of the two wires 3, for in this improved molding one wire can change its relative relation to the enclosing molding independent 65 of the other wire so that one wire may assume one position while the other may be forced to assume an entirely different position as indicated in Fig. 3 in order to provide for the necessary bending of the molding. It must, therefore, be apparent that the two wires not 70 only stiffen the molding but they also permit the molding to be readily bent into all necessary forms, reducing the tendency to buckle and lessening the danger of the fastening devices drawing the molding out of the desired 75 shape.

Without further analysis, the foregoing will so fully reveal the gist of this invention that others can, by applying current knowledge, readily adapt it for various utilizations 80 by retaining one or more of the features that, from the standpoint of the prior art, fairly constitute essential characteristics of either the generic or specific aspects of this invention and, therefore, such adaptions should 85 be, and are intended to be, comprehended within the meaning and range of equivalency of the following claim.

Having thus revealed this invention, I claim as new and desire to secure the following combinations and elements, or equivalents thereof, by Letters Patent of the United States:—

As a new article of manufacture, a finishing molding strip, the same consisting of a 95 thick compact filler strip formed from paper, having a substantial amount of stretch, formed into a plurality of narrow folds, a plurality of independent metal members imbedded within the folds of paper and extending longitudinally through said strip, the said metal members having independent movement, one of the other, and independent of the paper strip whenever said strip is bent into an abnormal position. 100

In witness whereof, I have hereunto subscribed my name.

EDGAR R. CREAMER.
